Primary Examiner — Ruth McInroy(74) *Attorney, Agent, or Firm* — Knoble Yoshida & Dunleavy, LLC(57) **CLAIM**

The ornamental design for a combined barbecue shelf and console, as shown and described.

DESCRIPTION

FIG. 1 is an isometric view of a combined barbecue shelf and console showing our new design;

FIG. 2 is a front view thereof;

FIG. 3 is a top plan view thereof; and,

FIG. 4 is a side view thereof.

The details shown in broken lines are for illustrative purposes only and form no part of the claimed design.

1 Claim, 4 Drawing Sheets
